Patented May 18, 1920.

2 SHEETS—SHEET 2.

UNITED STATES PATENT OFFICE.

CHARLES E. NILES, OF FARGO, NORTH DAKOTA.

CLOTHES-REEL.

1,340,494.

Specification of Letters Patent.

Patented May 18, 1920.

Application filed January 13, 1919. Serial No. 270,906.

To all whom it may concern:

Be it known that I, CHARLES E. NILES, a citizen of the United States, residing at Fargo, in the county of Cass and State of

5 North Dakota, have invented certain new and useful Improvements in Clothes-Reels, of which the following is a specification.

This invention relates to an improved clothes reel and has as its primary object to 10 provide a device of this character so constructed that the reel may be adjustably raised or lowered upon its standard.

The invention has as a further object to provide a construction wherein the reel will 15 be mounted to turn about its carrier.

And the invention has as a still further object to provide an improved type of reel support and lock.

Other and incidental objects will appear 20 during the course of the detailed description of the invention. In the drawings, wherein I have illustrated the preferred embodiment of the invention, and wherein similar reference characters designate corresponding parts throughout the several views:

Figure 1 is an elevation of my improved reel, this view showing in dotted lines, the manner in which the reel may be lowered upon its standard,

30 Fig. 1^a is a fragmentary sectional view showing the socket for the reel standard,

Fig. 2 is a fragmentary plan view particularly illustrating the mounting of the tie rods for the reel arms,

35 Fig. 3 is a fragmentary vertical sectional view more particularly illustrating the mounting of the support within the standard,

Fig. 4 is a fragmentary perspective view 40 showing one of the locks employed for holding the support in vertically adjusted position and also illustrating the manner in which the lower end of said support is formed to receive said lock,

45 Fig. 5 is a fragmentary perspective view looking downwardly upon the upper end of the reel carrier,

Fig. 6 is a transverse sectional view taken 50 on the line 6—6 of Fig. 3 and looking downwardly,

Fig. 7 is a detail perspective view of the collar employed to carry the tie rods for the reel arms,

55 Fig. 8 is a fragmentary vertical sectional view showing the stop employed for the

lower end of the spring used in connection with the reel supporting member, and

Fig. 9 is a perspective view showing the stop in detail.

In carrying the invention into effect I employ a tubular post or standard 10 which is removably received at its lower end in a socket 10^a snugly receiving the standard. The socket is sunk into the ground so as to support the standard in upright position 60 and, when the standard is removed therefrom, may be closed by a cap 10^b, this cap being preferably connected with the socket by a short length of chain. Formed in one side of the standard is a longitudinally extending slot 11 and closing said standard at its upper end is a cap 12 detachably connected therewith. Telescopically fitting within the standard is a supporting member 13 provided, as best shown in Figs. 3 and 4 65 of the drawings, with a reel carrier at its upper end and adjusting and locking mechanism at its squared lower end portion. Formed through the end portion 14 of said member are spaced pockets or openings 15 70 divided by an intermediate forwardly extending web 16. Fulcrumed at their inner ends within the pockets are reversely presented locking dogs 17. At their outer ends these dogs are extended to provide handles 80 18, while at their inner ends they are formed with reduced terminals 19 loosely engaging respectively with the top and bottom walls of the pockets 15. Shoulders 20 are provided on opposite sides of the dogs, and in 85 spaced relation to said shoulders are other shoulders 21. The shoulders 20 confront the outer face of the standard walls at opposite sides of the slot 11 while the shoulders 21 confront the inner face of the walls, and each pair of shoulders 20, 21 is spaced so as 90 to bite the wall when the dog is canted. Between the handles is a spring 22 tending to separate the dogs at their outer ends and yieldably hold the shoulders thereof in biting engagement with the standard. Thus, 95 it will be seen that by grasping the handles 18 of the dogs and moving them toward each other, the support will be unlocked and may then be adjusted vertically upon the 100 standard when, by releasing the handles, the dogs 17 will grip the standard for again locking said member against movement. In 105 this connection, it will be noted that the reduced terminals 19 are formed with curved 110

outer end edges in order that said terminals may freely rock within the pockets 15 of the squared portion 14 of the supporting member and for a similar reason, the upper 5 and lower walls of the respective openings are cut away at their outer end portions. Inward movement of the terminals toward each other will, of course, be limited by the dividing web 16.

- 10 Carried by the upper end of the support is a skeleton sleeve 23 surrounding the standard 10 and connected with the supporting member by vertically aligned webs 24 projecting through the slot 11 in the standard.
- 15 At its lower end the sleeve is provided with a radial flange 25 while, adjacent its upper end, the sleeve is inwardly offset to form a shoulder 26. Surrounding the sleeve and rotatably fitted on the flange is a collar 27. At 20 spaced points thereabout this collar is, as best shown in detail in Fig. 6, provided with pairs of ears or radially projecting lugs 28 and pivotally mounted between the lugs of each pair is an arm 29, these arms thus projecting radially from the sleeve 23. Threaded through the arms or otherwise connected thereto is a series of clothes lines 30 spaced longitudinally of the arms with respect to each other, these lines thus being intended 25 for receiving the clothes to be dried. Surrounding the sleeve 23 to rest upon the shoulder 26 thereof is a second and smaller collar 31 rotatable upon the sleeve. At its upper end this collar is formed with a quintagonal 30 portion providing a series of angular faces or sides 32 corresponding in number to the number of arms 29. Pivotally engaged at their inner ends one with each of the sides 32 of the collar, are tie rods 33, the outer 35 ends of which are pivoted to the inner portions of the arms 29 so that these rods will thus support the arms in upwardly and outwardly inclined position with respect to the standard.
- 40 Within the lower end portion of the standard is a stop 34 provided with a depending segmental flange 35 and fitted through this flange to extend through the slot 11 of the standard is a bolt or other suitable fastening device 36. As will be clear, by releasing this bolt, the stop may be adjusted vertically of the standard when the bolt may again be tightened for securing the stop in position. Resting at its lower end upon this stop is a 45 cushioning spring 37 the upper end of which is engaged with the lower end of the support 13 and is, as best shown in Fig. 3, received over a centering boss carried by the same.
- 50 As will now be readily understood in view of the preceding description, the support 13 may, by releasing the lock, be lowered within the standard 10 in the manner suggested in dotted lines in Fig. 1 so that clothes or 55 other articles to be dried may be readily

hung upon the reel. Then, by again grasping the handles of the lock the same may be released and the support elevated upon the standard for lifting the reel which, when the locking dogs are freed, will be relocked 70 in elevated position. In this connection, it will be noted that the spring 37 will, of course, act to materially assist in the operation of elevating the reel. If desired, the reel may be rotated upon the support about 75 the carrier 23 thereof so that when hanging clothes upon the reel or removing the clothes therefrom, it will be found unnecessary to walk around the reel.

Attention is now directed to the fact that 80 by lowering the support so as to bring the collar 31 within easy reach, this collar may be lifted from the carrier 23 for thus folding the reel arms 29 upwardly in vertical position. All of the arms will thus lie close 85 together so that said arms may be grasped and lifted upwardly to also displace the collar 27 from the carrier 23. With the reel thus detached from the support, the standard 10 may now be displaced from its socket 90 10^u and the entire device thus collapsed. This construction provides an arrangement whereby the device may be easily stored when not in use and thus protected from the weather. I accordingly provide a particularly efficient type of clothes reel while, at 95 the same time, the device is characterized by unusual structural simplicity.

As the collars 27 and 31 may be readily detached for removing the reel and the tie 100 rods 33, the standard may, if desired, be permanently secured in the ground and the reel and bracing means therefor applied when it is desired to use the drier.

Having thus described the invention, 105 what is claimed as new is:

1. A clothes drier including a tubular standard having a longitudinal slot, a vertically slidable elongated support arranged within the tubular standard, superposed 110 spaced webs carried by the upper portion of said elongated support and extending through said slot, a sliding sleeve surrounding said standard and connected at its ends to said webs, a clothes supporting device removably 115 carried by the upper and lower ends of said sleeve, and a locking device carried by the lower end of said support and extending through said slot.

2. A clothes drier including a tubular 120 standard having a longitudinal slot, a vertically adjustable support arranged within the standard, superposed spaced webs carried by said support and extending through said slot, a sliding sleeve surrounding said standard and connected to said superposed spaced webs, an annular flange formed integral with the lower portion of said sleeve and extending outwardly therefrom, a collar 125 surrounding said sleeve and mounted on said 130

flange, a plurality of clothes supporting devices connected to said collar, the upper portion of said sleeve being reduced for forming an exterior annular shoulder, a second 5 collar surrounding said sleeve and removably engaging said annular shoulder, and bracing devices connected to said second named collar and engaging said clothes supporting devices, said first and second named 10 collars being readily detachable whereby said clothes supporting and said bracing devices may be readily removed from said standard.

3. A clothes drier including a tubular 15 standard having a longitudinal slot, a vertically adjustable support arranged within the tubular standard, webs carried by said support and extending through said slot, a sleeve surrounding the standard and connected to said webs, clothes supporting de- 20

vices connected to said sleeve, and an adjustable stop element arranged within said tubular standard below said support and adapted to limit the downward movement of the same.

4. A clothes drier including a tubular standard having a longitudinal slot, a vertically adjustable support arranged within the standard and provided with spaced webs extending through said slot, a sleeve surrounding said standard and connected to said webs, clothes supporting devices carried by said sleeve, an adjustable stop element arranged within said tubular standard below said support and having a fastening device extending through said slot, and a cushioning element mounted upon said stop element.

In testimony whereof I affix my signature.

CHARLES E. NILES. [L. S.]
